CONTROL SYSTEM

Joe Weber, Irwin, Pa., assignor to Westinghouse
Electric & Manufacturing Company, East Pitts-
burgh, Pa., a corporation of Pennsylvania

Application May 14, 1941, Serial No. 393,391

7 Claims. (Cl. 80—35)

My invention relates, generally, to control systems, and more particularly, to a control system for a steel strip rolling mill and the like.

It has been found that, with all other conditions remaining constant, the amount of reduction of a strip of steel as it passes through a strip mill varies with the speed at which the reducing rolls are driven. Thus, when the mill is accelerated and decelerated from and to the speed required for threading the mill, the strip produced is of larger gauge than that produced while the mill is running at normal speed.

An object of the invention is to provide a control system for a strip rolling mill which shall function to compensate for the variations in strip gauge when the speed of the mill is varied.

Another object of the invention is to provide a control system for a strip rolling mill which shall function to automatically vary the tension on a strip in a strip rolling mill in accordance with variations in the speed of the mill to thus compensate for strip gauge variations due to the speed variations of the mill.

A further object of the invention is to provide a control system for a strip rolling mill which shall function to automatically control the tension and/or the screw-down setting of the mill in accordance with the speed of the mill to thereby compensate for strip gauge variations occasioned by variations of the speed of the mill.

Another object of the invention is to provide a control system for a work device which acts upon a length of material as it passes through the device which shall function to control the tension on the length of material as it passes through the work device in accordance with the speed of travel of the length of material.

A further object of the invention is to provide a control system for a strip rolling mill which shall function to automatically control the tension on a length of material as it passes through the mill within predetermined tension limits and which shall function to vary the spacing of the reducing rolls of the mill when these predetermined tension limits are reached.

These and other objects and advantages of the invention will be apparent from the following detailed description taken in connection with the accompanying drawings, in which like reference characters designate similar elements and in which:

Figure 1 is a control diagram for a strip rolling mill embodying the principal features of a preferred embodiment of the invention;

Fig. 2 is a control diagram for a strip rolling mill embodying the principal features of another embodiment of the invention.

In the embodiment of the invention shown in Fig. 1, a tensioning roller 10 is made to bear upon a strip 12 as it passes between the roll stands 14 and 16 of a strip rolling mill. The tensioning roller 10 may be actuated by a pressure fluid operated piston 18 and a regulator 20 controls the drive motor 22 for the roll stand 14 to keep the tensioning roller 10 within predetermined limits of strip deflection. A fluid pressure regulating valve 24 controls the fluid pressure acting upon the piston 18 and thereby controls the tension on the strip. A solenoid 26 may be variably energized by a circuit including a variable resistor 28 to vary the fluid pressure acting on the piston 18 to thereby vary the strip tension. The operation of the tensioning roller 10 to tension the strip, the regulator 20, and the regulating valve 24 under the influence of the solenoid 26 is described in the patent to W. G. Cook, No. 2,223,718, issued December 3, 1940, and reference is made to this patent for a detailed description of the operation of these elements.

A second solenoid 30 is disposed in operative relation with the regulating valve 24 and this solenoid is energized in accordance with the speed of the drive motor 32 for the roll stand 16 to thus vary the strip tension in accordance with the speed of the mill.

A screw-down control system 34 is also controlled in accordance with the speed of the mill to thereby vary the spacing of the reducing rolls of the roll stand 16 in accordance with variations in the mill speed.

In the embodiment of the invention shown in Fig. 2, the screw-down setting of the roll stand 16 is controlled by a fluid pressure responsive control device 36 in accordance with the fluid pressure acting to tension the strip 12 and acts to control the screw-down setting of the roll stand 16 and the tension on the strip when the strip tension reaches predetermined limits.

Referring again to Fig. 1 for a more detailed description of the invention, a pilot generator 38 is driven by the mill motor 32 by means of a shaft 40 and has its field winding 42 continuously energized at a substantially constant potential. The winding of the solenoid 30 is connected to be energized by the generator 38 in a circuit which extends from one terminal of the generator 38 through a conductor 44, the winding of the solenoid 30, a conductor 46, a circuit control device 48, a conductor 50, a variable resistor 52 and a

conductor 54 to the other terminal of the generator 38.

The solenoids 26 and 30 are disposed to oppose each other so that increased energization of the solenoid 26 tends to increase the fluid pressure acting upon the piston 18 and increased energization of the solenoid 30 tends to decrease the fluid pressure acting upon the piston 18. Thus as the speed of the mill increases, the energization of the solenoid 30 will be increased to decrease the fluid pressure on the piston 18 and to thereby decrease the tension on the strip 12. In this way, the reducing forces on the strip 12 may be made to remain substantially constant since the increased reduction due to the increased speed of the mill will be compensated for by decreased strip reducing forces due to the decrease in the tension of the strip as it passes through the mill. The variable resistor 52 may be adjusted as desired to provide whatever degree of compensation is necessary.

The mechanism 56 for adjusting the screw-down setting of the mill is driven by a motor 58 through a shaft 60. The motor 58 has a field winding 62 which may be selectively energized by relays 64 and 66 to cause the motor 58 to rotate in the desired direction to either increase or decrease the spacing of the reducing rolls of the mill stand 16. The field winding 62 of the motor 58 may be energized by the relay 64 to cause the screw-down setting of the mill to increase the spacing of the reducing rolls to thereby give decreased reduction of the strip 12 in a circuit extending from a conductor X, which may be connected to one terminal of any suitable source of direct current power, through a conductor 68, contact element 70 of the relay 64, a conductor 72, the field winding 62, conductors 74 and 76, contact element 78 of the relay 64 and conductors 80 and 82 to the conductor Y, which may be connected to the other terminal of the source of direct current power. The motor 58 may be caused to rotate in the opposite direction by providing an opposite polarity of energization for the field winding 62 as the result of the energization of the relay 66 in a circuit which extends from the conductor X through conductors 68 and 84, contact element 86 of the relay 66, the conductor 74, the field winding 62, conductors 72 and 88, contact element 90 of the relay 66 and conductors 80 and 82 to the conductor Y.

A solenoid 92 is connected to be energized by the pilot generator 38 in a circuit which extends from one terminal of the generator 38 through conductors 44 and 94, a circuit control device 96, a conductor 98, a variable resistor 100, a conductor 102, the winding of the solenoid 92, and conductors 104 and 54 to the other terminal of the pilot generator 38. The solenoid 92 is thus energized in accordance with the speed of the mill motor 52 and actuates a movable contact element 106 which is disposed to engage contact element 108, or 110, when an increase or decrease of the energization of the solenoid 92 occurs. The relay 64 is energized by the engagement of the contact elements 106 and 108 in a circuit which extends from the conductor X through conductor 112, contact elements 106 and 108, a conductor 114, the winding of the relay 64 and conductors 116 and 82 to the conductor Y.

A similar circuit for energizing the relay 66 is controlled by the contact elements 106 and 110 and extends from the conductor X through the conductor 112, contact elements 106 and 110, 75

a conductor 118, the winding of the relay 66 and conductors 116 and 82 to conductor Y. The spaced contact elements 108 and 110 are mounted upon a sleeve 120 having screw-threaded engagement with a shaft 122 which is driven by the shaft 60 through gear members 124 and 126.

Thus when the speed of the mill 16 increases, the output potential of the pilot generator 38 will increase which will, in turn, cause increased 10 energization of the solenoid 92 and the engagement of the contact elements 106 and 108. This will cause the relay 64 to be energized to, in turn, cause the motor 58 to drive the screw-down mechanism 56 in a direction to decrease the 15 screw-down setting or increase the reducing roll spacing of the mill stand 16 to thus compensate for the increased reduction of the strip 12 due to the increased speed of the mill 16. The variable resistor 100 may be adjusted as desired to 20 provide any desirable compensation by variation of the screw-down setting. The circuit control devices 48 and 96 which control the circuits of the solenoids 30 and 92 may be opened or closed as desired to provide either tension compensation 25 or screw-down compensation or both with variations of speed in the mill.

In the embodiment of the invention shown in Fig. 2, the pilot generator 38 is connected to energize the solenoid 30 in a circuit which extends 30 from one terminal of the generator 38 through a conductor 128, a variable resistor 130, a conductor 132, the winding of the solenoid 30, a conductor 134, a variable resistor 136, and a conductor 138 to the other terminal of the generator 38. This circuit will function to vary the tension applied to the strip 12 by the tension roll 10 in inverse proportion to the speed of the mill 32.

The pressure responsive device 36 is connected to the conduit 140, which extends between the 40 regulating valve 24 and the piston 18, to be responsive to the fluid pressure acting upon the piston 18 and to be energized, therefore, in accordance with variations in the tension on the strip 12 which, in turn, is a function of the speed 45 of the motor 32 and the mill stand 16. The pressure responsive device 36 is disposed to actuate a movable contact element 142 and fixed adjustable contact elements 144 and 146 are disposed in the path of travel of the contact element 142 to 50 be engaged thereby upon predetermined increase or decrease of the fluid pressure acting to tension the strip. The contact element 142 and cooperating contact elements 144 and 146 are disposed to control relays 64 and 66 to thereby 55 control the screw-down motor 58 and the screw-down mechanism 56 as described hereinbefore in the explanation of the operation of the embodiment of the invention shown in Fig. 1. The variable resistor 136 is connected to be actuated by a shaft 122 which, in turn, is actuated by the 60 shaft 60 through the gear members 124 and 126.

In the operation of the system shown in Fig. 2, any change in the speed of the mill 16 will cause a change in the fluid pressure acting on the piston 18 and will, therefore, cause a change in the tension on the strip 12 and when this tension is changed to the extent that the contact element 142 engages either the contact element 144 or 146, the screw-down setting will be changed accordingly and the actuation of the screw-down apparatus will, in turn, actuate the variable resistor 136 to change the fluid pressure acting on the piston 18. Thus, upon an increase in the speed of the mill 16, the tension on the strip 12 will be decreased. When there is sufficient de-

crease in tension on the strip 12 to permit the contact elements 142 and 146 to engage, the screw-down setting of the mill stand 14 will be decreased and this decrease in the screw-down setting will so actuate the variable resistor 136 as to decrease the energization of the solenoid 30 and thereby increase the fluid pressure sufficiently to cause the contact element 142 to be disengaged from the contact element 146. In a similar manner, a decrease in speed of the mill will cause a corresponding increase in the tension on the strip 12 until the contact element 142 engages the contact element 144 at which time the screw-down setting of the reducing rolls in the mill stand 16 will be varied to decrease the spacing of the reducing rolls and the variable resistor 136 will be so actuated as to increase the fluid pressure to disengage the contact elements 142 and 144.

Thus compensation for the variation in the strip thickness due to variations in the speed of the mill will be provided by variations in the tension on the strip 12 between predetermined limits of tension as determined by the setting of the contact elements 144 and 146 and compensation for variations in speed beyond the speed at which these contact elements function to vary the screw-down will be provided by the proper manipulation of the screw-down setting of the mill. The variable resistor 130 may be adjusted as desired to provide any desired degree of energization of the solenoid 30.

Thus it will be seen that I have provided a control system for a work device which acts upon a length of material as it passes through the work device which shall function to control the forces acting upon the length of material in response to the speed of travel of the length of material through the work device.

In compliance with the requirements of the patent statutes, I have shown and described herein the preferred embodiments of my invention. It is to be understood, however, that the invention is not limited to the precise constructions shown and described but is capable of modification by one skilled in the art, the embodiments herein shown being merely illustrative of the principal features of my invention.

I claim as my invention:

1. In a control system for a strip rolling mill, means responsive to variations of the speed of the mill, and means controlled by said speed responsive means for varying the screw-down setting of the mill to thereby compensate for variations in the reduction of the strip due to changes in the speed of the mill.

2. In a control system for a strip rolling mill, means responsive to variations of the speed of the mill, and means controlled by said speed responsive means for varying the tension on the strip and the screw-down setting of the mill as the strip passes through the mill to thereby compensate for variations in the reduction of the strip due to variations in the speed of the mill.

3. In a control system for a strip rolling mill, means subjecting a strip of material to tension as it passes through the mill, force applying means for actuating said strip tensioning means, means responsive to the speed of the mill for

controlling the force applied to said actuating means to thereby control the tension on the strip, and means responsive to the force applied by said force applying means for controlling the screw-down setting of the mill.

4. In a control system for a strip rolling mill, means subjecting a strip of material to tension as it passes through the mill, force applying means for actuating said strip tensioning means, means responsive to the speed of the mill for controlling the force applied to said actuating means to thereby control the tension on the strip, and means responsive to the force applied by said force applying means for controlling the screw-down setting of the mill, and means controlled by the screw-down control means for controlling the force applied by said force applying means.

5. In a control system for a strip rolling mill, means engaging a strip of material as it passes through the mill to thereby subject the strip to tension, pressure fluid operated means for causing said means to subject the strip to a tension which is a function of the fluid pressure acting on the pressure fluid operated means, means responsive to variations of the speed of the mill, and means whereby said speed responsive means controls the fluid pressure acting on the pressure fluid actuated means to thereby vary the strip tension in accordance with variations of the speed of the mill.

6. In a control system for a strip rolling mill, means engaging a strip of material as it passes through the mill to thereby subject the strip to tension, pressure fluid operated means for causing said means to subject the strip to a tension which is a function of the fluid pressure acting on the pressure fluid operated means, means responsive to the speed of the mill, means whereby said speed responsive means controls the fluid pressure acting on the pressure fluid actuated means to thereby vary the strip tension in accordance with the speed of the mill, means for varying the spacing of the reducing rolls of the mill, and means responsive to the fluid pressure acting on the pressure fluid actuated means for controlling said reducing roll spacing varying means.

7. In a control system for a strip rolling mill, means for engaging a strip of material as it passes through the mill to thereby subject the strip to tension, pressure fluid operated means for causing said bearing means to subject the strip to a tension which is a function of the fluid pressure acting on the pressure fluid operated means, means responsive to the speed of the mill, means whereby said speed responsive means controls the fluid pressure acting on the pressure fluid actuated means to thereby vary the strip tension in accordance with the speed of the mill, means for varying the spacing of the reducing rolls of the mill, means responsive to the fluid pressure acting on the pressure fluid actuated means for controlling said reducing roll spacing varying means, and means responsive to the actuation of said roll spacing varying means for varying the fluid pressure acting on said pressure fluid actuated means.

JOE WEBER.
